UNITED STATES PATENT OFFICE.

FREDERICK SEABERG, OF CHICAGO, ILLINOIS, ASSIGNOR TO NATIONAL DUMP CAR COMPANY, A CORPORATION OF MAINE.

DUMP-DOOR-OPERATING MECHANISM.

992,607.

Specification of Letters Patent. Patented May 16, 1911.

Application filed February 6, 1909. Serial No. 476,524.

To all whom it may concern:

Be it known that I, FREDERICK SEABERG, a citizen of the United States, residing at Chicago, in the county of Cook and State 5 of Illinois, have invented certain new and useful Improvements in Dump-Door-Operating Mechanism, of which the following is a specification.

The object of my invention is to provide 10 improved means for operating the doors of dump cars.

Among the objects attained by my invention is the provision in a chain operated door of means for supporting the door independently of the chain when the same is closed. The manner of accomplishing this 15 and other objects of my invention will more clearly appear from the following description and claims, taken in connection with the 20 accompanying drawings, in which—

Figure 1 is an end view of a car, partly broken away, showing the doors in closed position. Fig. 2 is a view corresponding to Fig. 1, showing the doors open. Fig. 3 is 25 a side elevation of the end portion of the car. Fig. 4 is a detail view of the adjoining portions of two doors, together with part of the operating mechanism. Fig. 5 is an end view of the part of the structure shown in 30 Fig. 4. Figs. 6 and 7 are detail views of the connection between adjoining ends of the sectional operating shaft.

In the accompanying drawings, I have 35 illustrated one specific form of mechanism embodying my invention, but the principle of the invention is not dependent upon the specific mechanism there illustrated and may be applied in other forms.

The car illustrated in the present instance 40 comprises a center sill composed of channel beams 1 connected by webs 2 and cross plates 3. Extending transversely of the car and resting upon the center sill are the cross sills 4, and a longitudinal central floor plate 5 lies above the center sill and is supported 45 upon pedestals 6, to which the hinge plates 7 are also secured. Upon each side of the center sill and hinged to the plates 7 is a longitudinal series of dump doors 8, each 50 door occupying the opening framed by the center sill, the adjoining cross sills and the car side. The doors of each series are operated by means of a winding shaft designated generally by the numeral 9. Preferably, half of the doors upon each side of the

center sill are operated by a winding shaft 9 extending inwardly from the end of the car half the length thereof. Each winding shaft 9 comprises bearing parts rotatably mounted in the ends of the cross sills, and 60 eccentric door supporting sections between the cross sills and opposite the doors. The bearings of the operating shaft in the cross sills are located inside of the outer edge of the door when the latter is in closed position, 65 and winding chains are secured at one end to said operating shaft and at the other end to said doors. The eccentricity of the door supporting sections of the operating shaft is sufficient to cause said parts to lie outside 70 of the outer edges of the doors when the shaft is rotated in the proper direction, and the parts are so disposed and proportioned that at the time the doors reach the level of the operating shaft the eccentric portion 75 is directed outwardly, thereby affording clearance for the passage of the door, after which the continued rotation of the operating shaft brings the eccentric section beneath the doors to take the strain of the 80 doors and superposed load off from the operating chains. When the doors are closed, as above described, the eccentric sections of the operating shaft will lie in substantially 85 the same vertical plane with the supporting journals of the shaft, thereby avoiding any tendency due to the weight of the doors and load to rotate the shaft.

Referring in detail to the construction 90 illustrated, the operating shaft consists of 95 separate sections 9'. Each of the sections 9' is bent to the form of a crank having a central eccentric section offset from the end or bearing sections. In the present instance, I have shown the sections 9' connected by 100 means of a sleeve 10, which is cored out axially, as indicated at 11 in Figs. 6 and 7. Adjacent the ends, the axial opening 11 extends radially through the sleeve, as indicated at 12. When the sections 9' are inserted in the sleeve 10, the crank arm parts thereof lie in the part 12 of the opening of the sleeve 10, thus preventing rotation of the connected sections and sleeve. For the purpose of insuring the parts against displacement, bolts 13 may be passed through openings in the sleeve and shaft sections, and eyes 14 in the ends of these bolts may be utilized for the purpose of attaching the operating chains 15. The sleeves 10 serve 110

not only as a coupling between the ends of the sections 9', but also serve as a winding drum for the operating chain. The sleeves 10 are journaled in openings in the cross bearers 4 and are further supported by bearings in hangers 16 depending from and secured to the floor plate 17. Preferably, the hangers 16 and cross bearer 4 are spaced apart and the winding chain received between them. At their opposite ends the winding chains may be secured in any suitable manner to the dump doors adjacent their outer edges. In the present instance I have provided for this connection by means of castings 18 secured to the under sides of the doors at their outer corners and provided at their lower ends with openings to receive short cross shafts 19 which extend beneath the cross sills and afford a connection between adjoining doors. The ends of the operating chains are connected to the connected cross shafts 19. It is not essential, however, to the application of the broad principle of my invention that the adjoining doors be connected as above described and that the operating chains be connected to the doors through the medium of the member which extends between the doors; and the principal form of sectional operating shaft described, while forming a convenient means of applying my invention, is not indispensable, as the operating shaft with eccentric sections might be otherwise constructed.

Any suitable means may be employed for imparting rotation to the operating shaft. In the present instance I have shown a hand lever 21 provided with a reversible pawl 22 adapted to coöperate with a pinion 23 secured to the end of the operating shaft beyond the end wall of the car. A detent 24 also coöperates with a pinion upon the shaft 9 to restrain the same against accidental movement.

Referring to Fig. 2 of the drawings, it will be apparent that when the operating shaft is rotated in counter clockwise direction, the door will be raised by the winding chain, and, as above stated, the parts are so arranged and proportioned that when the outer edge of the door reaches the level of the operating shaft the eccentric portion of the shaft will be directed outwardly, thus affording clearance for the door to pass the shaft, after which the continued rotation of the operating shaft will carry the eccentric part of the shaft beneath the door, as illustrated in Fig. 1. In this position the eccentric part of the shaft lies in the same vertical plane with the supporting bearings of the shaft, whereby there is no component of the weight of the door and load tending to rotate the shaft. In the present instance, the shaft 9 is shown as supporting the door through its contact with the under sides of

the castings 18, said castings being formed with a curved bearing surface conforming to the path of movement of the eccentric part of the shaft as it rides beneath the outer edges of the doors.

I claim:—

1. In a dump car a door hinged at one edge, a rotatable operating shaft journaled adjacent the free edge of said door, said shaft having a chain-winding section and an eccentric door-supporting section, and a chain connected to said shaft and door. 70
2. In a dump car a door hinged at one edge, a rotatable operating shaft journaled beneath the outer part of said door, said shaft having an eccentric section opposite said door so proportioned as to clear said door when said shaft is rotated, and a chain extending from said shaft to said door. 75
3. In a dump car a door hinged at one edge, a rotatable operating shaft journaled adjacent the free edge of said door, said shaft having concentric chain-winding sections mounted in bearings at the sides of said door and an eccentric door-supporting section opposite said door, and a chain connected to said shaft and door. 80
4. In a dump car a door hinged at one edge, a rotatable operating shaft journaled adjacent the free edge of said door, said shaft having concentric chain-winding sections mounted in bearings at the sides of said door and an eccentric door-supporting section opposite said door, a chain connected to said shaft and door, the parts being so proportioned that when said chain is wound on said shaft to close said door said eccentric section will lie beneath said door in substantially the same vertical plane with said concentric chain-winding sections. 85
5. In a car an underframe, hinged dump doors, a sectional shaft journaled in said underframe adjacent the free edges of said doors, each section comprising a concentric bearing part and an eccentric door-supporting part, and connecting members between said sections. 90
6. In a car an underframe, hinged dump doors, a sectional shaft adjacent the free edges of said doors, each section comprising an eccentric door-supporting part, connecting members journaled in said underframe and non-rotatably engaging the adjacent ends of said sections, and winding chains secured to said connecting members and to said doors. 95
7. In a car, an underframe, dump doors, a shaft journaled adjacent the free edges of said doors, said shaft having eccentric parts adapted in one position of said shaft to underlie and support said doors and in another position to clear the edges of said doors, chains secured to said shaft and doors, members connecting adjacent doors, and means for rotating said shaft. 100
8. In a car an underframe, hinged dump doors, a shaft journaled adjacent the free edges of said doors, said shaft having eccentric parts adapted in one position of said shaft to underlie and support said doors and in another position to clear the edges of said doors, chains secured to said shaft and doors, members connecting adjacent doors, and means for rotating said shaft. 105
9. In a car an underframe, hinged dump doors, a shaft journaled adjacent the free edges of said doors, said shaft having eccentric parts adapted in one position of said shaft to underlie and support said doors and in another position to clear the edges of said doors, chains secured to said shaft and doors, members connecting adjacent doors, and means for rotating said shaft. 110
10. In a car an underframe, hinged dump doors, a shaft journaled adjacent the free edges of said doors, said shaft having eccentric parts adapted in one position of said shaft to underlie and support said doors and in another position to clear the edges of said doors, chains secured to said shaft and doors, members connecting adjacent doors, and means for rotating said shaft. 115
11. In a car, an underframe, dump doors, a shaft journaled adjacent the free edges of said doors, said shaft having eccentric parts adapted in one position of said shaft to underlie and support said doors and in another position to clear the edges of said doors, chains secured to said shaft and doors, members connecting adjacent doors, and means for rotating said shaft. 120
12. In a car, an underframe, dump doors, a shaft journaled adjacent the free edges of said doors, said shaft having eccentric parts adapted in one position of said shaft to underlie and support said doors and in another position to clear the edges of said doors, chains secured to said shaft and doors, members connecting adjacent doors, and means for rotating said shaft. 125
13. In a car, an underframe, dump doors, a shaft journaled adjacent the free edges of said doors, said shaft having eccentric parts adapted in one position of said shaft to underlie and support said doors and in another position to clear the edges of said doors, chains secured to said shaft and doors, members connecting adjacent doors, and means for rotating said shaft. 130

8. In a car an underframe comprising central and transverse sills, a longitudinal series of doors framed between said sills and hinged adjacent the longitudinal center of the car, connecting members, each secured to adjacent doors and extending beneath said transverse sills, winding shafts and chains for raising and lowering said doors, said shafts having eccentric parts opposite said doors, said eccentric parts being adapted in one position of said shaft to underlie and support said doors and in another position to clear the edges of said doors.

9. In a car an underframe comprising central and transverse sills, a longitudinal series of doors framed between said sills and

hinged adjacent the longitudinal center of the car, connecting members, each secured to adjacent doors and extending beneath said transverse sills, a winding shaft journaled in 20 said transverse sills beneath the outer part of said doors, said shaft having eccentric sections opposite said doors so proportioned as to clear said doors when said shaft is rotated, and chains extending from said 25 shaft to said connecting members.

In testimony whereof, I have subscribed my name.

FREDERICK SEABERG.
